CHARLES BIRNBAUM, OF NEW YORK, N. Y.

RING SETTING

Application filed June 9, 1928. Serial No. 284,146.

This invention relates to ring settings and more particularly to that type of ring setting which is pivotally connected to the mount so that it may be hinged to expose a picture frame or other enclosure.

Heretofore in the manufacture of rings of this character it has been customary to assemble the setting and then solder a leaf of the hinge to the mount. This requires a high degree of skill in order that the setting may properly fit within the mount and be free to swing on its hinge. With my improved construction the setting or frame carrying the setting is hinged to a plate which fits within the mount, the plate and the setting frame having aligned sleeves for the reception of a pintle so that the parts are insured an accurate assemblage by the mere insertion of the pintle after the parts are constructed and assembled so that there is no necessity for soldering the hinge and consequently there is no possibility of imperfect results.

With these and other objects in view, the invention consists in certain novel features of construction and combinations and arrangements of parts which will be more fully hereinafter described and pointed out in the claims.

In the accompanying drawings—

Figure 1 is a view in section through a ring embodying my invention;

Figure 2 is a plan view of the ring with the setting swung outward;

Figure 3 is a plan view showing the three members of my improved setting which together form a complete series of sleeves to receive the pintle and hingedly connect them.

All of the views of the drawings are greatly exaggerated for purposes of illustration as it is of course to be understood that in the manufacture of the ring the parts illustrated will be very small.

1 represents the ring proper having an oblong-shaped open mount 2 or which may be of any desired shape and ornamentation. 3

represents a plate which fits within the mount 2 and is secured therein in any approved manner, as, for example, by solder. 4 represents a picture frame and 5 a setting frame, and this setting frame 5 may support a cameo, stone 50 or other ornament 6.

The setting plate 3 at one edge is provided with a series of spaced sleeves 7 and the setting plate 5 is also provided with a series of sleeves 8 spaced apart. The picture frame 4 55 is provided at one edge with sleeves 9 spaced apart, and all of these sleeves 7, 8 and 9 are disposed in alinement, as illustrated in Figure 2, with a pintle or pin 10 positioned in the sleeves so as to hingedly connect the several 60 parts of the ring.

It is to be observed of course that the plate 3 is sufficiently depressed to accommodate the picture frame 4 between the same and the setting plate 5, and the free edge of said setting 65 plate is snapped into closed position by its engagement with the edge of mount 2, as clearly illustrated at 11.

My invention is directed particularly to the manner of hinging the setting to the ring 70 mount, and by reason of this construction an absolute alinement and registration of the several parts is insured so that a perfect setting is had and the extremely difficult hinge soldering is entirely dispensed with. 75

Various changes and alterations might be made in the general form of the parts described without departing from my invention and hence I do not limit myself to the precise details set forth but consider myself 80 at liberty to make such changes and alterations as fairly fall within the spirit and scope of the appended claims.

I claim:

1. In combination with a ring having a 85 hollow mount, a plate secured in the mount, a setting, said plate and setting having alined sleeves at one edge, a pintle in said sleeves, and a picture frame located between the setting and the plate and having sleeves alining 90

with the first mentioned sleeves and also receiving the pintle.

2. In combination with a ring having a hollow mount, a setting assemblage including 5 a plate and a setting, the said setting and plate hingedly connected, said plate snugly fitting within the hollow mount and fixedly secured therein.

Signed at New York, in the county of New 10 York and State of New York, this 25th day of May A. D. 1928.

CHARLES BIRNBAUM.
